UNITED STATES PATENT OFFICE.

MOSES SIGINOFF, OF HATTIESBURG, MISSISSIPPI.

SHOE-HEEL REINFORCEMENT.

1,402,671.

Specification of Letters Patent. Patented Jan. 3, 1922.

Application filed May 13, 1920. Serial No. 381,114.

To all whom it may concern:

Be it known that I, Moses Siginoff, a citizen of the United States of America, residing at Hattiesburg, in the county of Forrest and State of Mississippi, have invented new and useful Improvements in Shoe-Heel Reenforcements, of which the following is a specification.

The object of the invention is to provide means for reenforcing the heels of shoes, slippers and like foot wear of the kind adapted particularly for women's wear and ordinarily designated as French or high heels, for the purpose of strengthening the same against breakage or detachment due to transverse strains, and with this object in view the invention consists in a construction and combination of parts of which a preferred embodiment is shown in the drawings 20 wherein:—

Figure 1 is a sectional view of a shoe having its heel provided with reenforcing means constructed in accordance with the invention.

Figure 2 is a view of the inner or arch plate.

Figure 3 is a perspective view of the heel plate.

Figure 4 is a front elevation of the heel plate.

The device consists essentially of a heel and shank plate 10 shown in detail and detached from the shoe in Fig. 3, and an arch plate 11 which is disposed within the shoe between the outer sole and the insole as shown in Fig. 1 and extending preferably from the rear counter of the shoe to a point approaching the tread or extending substantially over the arch of the shoe, so that when the base plate 12 of the heel and shank plate 40 is disposed in parallelism with the arch plate and is secured thereto as indicated in Fig. 1 by screws 13 or the equivalent thereof, there is established a relation between the arch of the shoe and the body of the heel 14 which 45 serves to maintain the proper position of the latter regardless of strains which may be applied transversely thereto. The heel and shank plate in addition to the base member 12 which in practice is located between the 50 upper end of the heel proper and the adjacent surface of the outer sole 15 of the shoe, includes a heel facing member 16 shaped to conform to the heel, and a terminal ear 17 which is interposed between the body 14 of 55 the heel and the heel facing or tread 18

where it may be engaged by screws 19 or like fastening means. Obviously the heel facing may be renewed or replaced without disturbing the reenforcing element which is disposed to practically enclose the body portion of 60 heel or at least to cover the upper, lower and front surfaces thereof, and this joint between the body proper of the heel of the arch of the shoe is fortified to prevent the breaking under of the heel by the extension of the 65 arch plate having a considerable distance in advance of the front surface of the heel as clearly indicated in Fig. 1.

It will also be obvious that reenforcing means embodying the invention may be 70 readily applied to the shoe heel in the course of manufacture or as a means of repairing a shoe, which has become damaged by the breaking of the heel, and the indicated location of the reenforcing device is such as not 75 to detract in any way from the neatness of the appearance of the shoe. Also the material of which the reenforcement is formed may be sufficiently light to add but slightly to the weight of the article and yet have 80 sufficient strength to resist the strains to which the heel may be subjected in ordinary use, particularly as the facing member 16 of the heel plate is preferably concave or arched to conform to the contour of the heel structure. 85

What is claimed is:—

1. A heel reenforcing device consisting of an arch plate for arrangement in parallelism with a shoe sole in extension from a point 90 near the counter thereof to a point in advance of the front of the heel, and a heel plate having a base member interposed between the shoe sole and the upper end of the heel and secured to said arch plate, said heel 95 plate being provided with a heel facing member attached to the front surface thereof.

2. A shoe heel reenforcing device consisting of an arch plate extending between the inner and outer soles, and spanning the arch 100 of the shoe, and a heel plate having a heel facing member and a base member, the latter being disposed between the upper end of the heel and the exterior surface of the outer sole, and engaged by means which secure the body 105 of the heel to the shoe sole.

3. A shoe heel reenforcing device consisting of an arch plate disposed in parallelism with the shoe sole in overlapping relation with the upper end of the heel, and a heel plate 110

having a base member interposed between the upper end of the heel and the shoe sole, a facing member disposed in contact with the front surface of the heel, and a bottom plate located between the lower end of the shoe heel body and the facing member thereof, and means being provided for securing said

base member and bottom each in fixed relation respectively with the extremities of the heel body.

In testimony whereof he affixes his signature.

MOSES SIGINOFF.
